UNITED STATES PATENT OFFICE.

HENRY GORTNER, OF NEW ALBANY, OHIO.

LIFTING-JACK.

SPECIFICATION forming part of Letters Patent No. 400,205, dated March 26, 1889.

Application filed July 10, 1888. Serial No. 279,565. (No model.)

To all whom it may concern:

Be it known that I, HENRY GORTNER, a citizen of the United States, residing at New Albany, in the county of Franklin and State of 5 Ohio, have invented new and useful Improvements in Lifting-Jacks, of which the following is a specification.

The invention relates to improvements in lifting-jacks; and it consists in the construction and novel combination of parts herein-after described, illustrated in the accompanying drawings, and pointed out in the appended claims.

In the drawings, Figure 1 is a perspective view of a lifting-jack embodying the invention. Fig. 2 is a central vertical section on line xx of Fig. 1. Fig. 3 is a vertical section at right angles to that shown in Fig. 2. Fig. 4 is a plan view of the improved jack.

Referring to the drawings by letter, A designates the main frame, composed of two similar side frames, B B, having the opposite guide-slots b b , and connected by bolts or otherwise at their lower ends to the horizontal base-block C, which has the outstanding extension c on one side.

D is a transverse bar connecting the two frames B above the guide-slots b .

E is the lifting-frame, having the head e to rest under the article to be raised, and the uprights e' , with a space or slot, e^2 , between them, which space registers with the guide-slots b . The uprights e' are located, respectively, between the corresponding bars of the 35 frames B.

The bar D is rectangular in cross-section, and fits nicely between the uprights e' of the lifting-frame. F is a transverse foot-block, rectangular in cross-section, secured to the 40 outer bar or upright, e' , and with its ends resting in the guide-slots b of the frames B, in which slots it moves smoothly. By means of the bar D, the guide-slots, and the foot-block the lifting-frame is guided vertically and prevented from getting out of alignment.

G G are two similar opposite parallel swinging standards pivoted at their lower ends upon opposite sides of the extension c , and H is a lever pivoted near its inner end between 45 the upper ends of said standards. The said lever has secured to its upper edge, above and

inward from its pivotal point, the bearing-plate I, bent on itself and having the transverse rod i in the bend at its inner edge.

J J are S-shaped link-bars, having their 55 upper ends journaled on the ends of the rod i and their lower ends on a transverse rod, K, that passes through the bearing-slots and through a rectangular block, L, that travels in said slots, and which is provided with perforations l , at right angles to said slots.

M is a pin, attached by a cord, m , to a staple, m' , secured to the outer edge of the outer bar, e' , of the lifting-frame, and adapted to pass through openings N in said bars, and 65 through registering-perforations l in the block L. By means of the said perforated block, the pin, and the openings N in the lifting-frame the latter can be adjusted to various heights to adapt itself to wagon-bodies or other 70 things that it is desired to lift. The sigmoid link-bars J, by having their upper ends bent downward and their lower ends bent upward, cause the pressure on the journals of the rods i K to act at all times nearly vertically, so that 75 there is little or no composition of motion. The lever H consequently raises the block L almost vertically, and, besides the power saved by the nearly-vertical lift, the said block is prevented from binding in the guide-slots b 80 and thereby producing friction, which would obstruct the motion of said block and lessen the power of the machine. When the lever H is completely or nearly depressed, the upper ends of the link-bars G stand somewhat inward in relation to their lower ends or slightly nearer the frames B. Consequently the pressure of any weight upon the top or head of the lifting-frame causes the latter to be held up 85 more firmly.

Having described my invention, I claim—

1. In a lifting-jack, the combination of the main frame composed of two parallel side frames provided with guide-slots, the lifting-frame arranged between the said side frames 95 and provided with blocks extending into the said guide-slots, and the pivoted lever H, connected by suitable links to the lifting-frame.

2. In a lifting-jack, the combination of the main frame composed of side frames, B B, provided with guide-slots b b , the lifting-frame located between the side frames, B, and

provided with a foot-block, F, which extends into the guide-slots b, the guide-block L, adjustably connected to the lifting-frame and extending into the guide-slots, and the pivoted lever H, connected by suitable links to the block L, substantially as described.

3. In a lifting-jack, the combination, with the main frame composed of side frames, B, provided with guide-slots b b and connected near their upper ends by the transverse bar D, of the lifting-frame arranged between the frames B B and provided with a longitudinal slot, e², registering with the slots b and sliding on the bar D, the adjustable bar L, arranged in the slot e² and provided with a series of perforations, l, adapted to register with perforations N in the sliding frame, the removable pin M, engaging the said registering apertures, and the pivoted lever connected by suitable links to the block L, substantially as specified.

4. In a lifting-jack, the main frame A, composed of the slotted side frames, B B, which are arranged on a suitable base, C, and connected by a transverse bar, D, in combination with the lifting-frame E, provided with a slot,

e², embracing the bar D, and having a foot-bar, F, extending into the slots of the side frames, the adjustable block L, arranged in the slot e² and held in place by a pin, M, engaging registering apertures in the lifting-frame and the block L, the pivoted lever H, and the S-shaped or sigmoid links J, connecting the lever to the opposite ends of the bar L, substantially as specified.

5. In a lifting-jack, the main frame provided with opposite guide-slots b b, and the lifting-frame mounted in the main frame and provided with slots extending into the guide-slots, in combination with the swinging standards G, pivoted to the base of the main frame, the lever pivoted between the upper ends of the standards, and the S-shaped or sigmoid links connecting the lever to the lifting-frame, substantially as specified.

In testimony that I claim the foregoing as my own I have hereto affixed my signature in presence of two witnesses.

HENRY GORTNER.
